ALBERT E. STRIPPEL, OF RIDGEFIELD PARK, NEW JERSEY

ADDRESSING MACHINE

Application filed October 15, 1927. Serial No. 223,390.

This invention relates to an improvement in addressing machines, and more specifically, to a stencil track for such machines.

Addressing machines as commonly constructed include the general features of a vertical stack of stencils to be used, a horizontal track for guiding and retaining the stencils in proper position while they are being fed in single file through the printing portion of the machine, and a receptacle for receiving the stencils from the track after they have been used. Machines of this sort may be divided into two types, one in which the stencils pass toward the operator from a stack at the rear to a receptacle in the front, and the other in which the stencils pass before the operator from a stack at one side to a receptacle at the other. The latter type has numerous points of advantage and the improvement of this invention relates particularly to tracks useful therein.

In further explanation it may be stated that stencil filing systems frequently require the attachment to certain stencils of small projecting tabs or "flags", generally metallic and colored or otherwise distinctively marked. Heretofore it has been necessary when using stencils in a machine of the second type, to remove any tabs attached thereto so as to have their margins unincumbered for passage along the tracks. The tabs so removed had, of course, to be replaced later, and it is apparent that very considerable annoyance resulted from this necessity for removal and replacement, in view of the fact that addressing machines are generally adapted to print approximately one hundred stencils per minute, and that a run may consist of from ten thousand to one million or more stencils, many of which will bear tabs as described. This necessity has, indeed, generally been regarded as prohibitively burdensome and resort has been had to machines of the first (back-to-front) type whenever tabbed stencils have been used in large quantities, with resulting disadvantage to manufacturers of addressing machines of the second type as well as to the users, since the latter machines are in many important respects preferable to the former.

An object of the invention is to provide a track for addressing machines of the second type, such that stencils bearing tabs may pass therethrough.

Another object is to provide such a track which will guide accurately and steadily both plain and tabbed stencils.

A further object consists in providing certain improvements in the form, construction and arrangement of the several parts, whereby the above named and other objects may effectively be attained.

A practical embodiment of the invention is represented in the accompanying drawings, in which

Fig. 1 represents a plan view of a pair of addressing machine tracks with a series of stencils passing therebetween, a portion of one track being broken away;

Fig. 2 represents an enlarged transverse section at the line II—II of Fig. 1, looking in the direction of the arrows;

Fig. 3 represents an enlarged detail longitudinal section at the line III—III of Fig. 1, looking in the direction of the arrows; and

Fig. 4 represents an enlarged detail transverse section at the line IV—IV of Fig. 1, looking in the direction of the arrows.

In the drawings, a plain track member of the form commonly in use is denoted by 1; this member includes a guide groove 2 adapted to embrace and support an edge 3 of a stencil 4. Parallel to the track member 1 and spaced therefrom is another track member 5, having a terraced form as shown in Figs. 2 and 4, including a lower horizontal portion 6, an undercut wall portion 7, an upper horizontal portion 8 and an upper vertical wall portion 9. A top plate 10 is secured to the top of the member 5 so as to extend substantially as far as its lower horizontal portion 6. The stencils are shown provided with tabs or "flags" 11, of a customary form.

Referring particularly to Fig. 2, it will be seen that the body of the stencil is retained in proper alinement by the groove 2 in the track member 1 and by the lower horizontal portion 6 and undercut wall portion 7 in the track member 5. This relationship obtains

quite irrespective of the tabs or "flags" 11. The latter project into the recess 12 formed by the upper horizontal portion 8, the upper vertical wall portion 9 and the top plate 10, and pass freely along said recess while the stencils are retained in position as stated above. Any tendency of the stencils 4 to get into the recess 12 is counteracted by the undercut formation of the wall portion 7 and, 10 additionally, by the provision of a small curved leaf-spring 13 secured to the top plate 10 in a suitable manner, as by screws 14 or the like, and projecting through an aperture 15 therein, as clearly shown in Figs. 3 and 4. While only one such spring is shown, it is 15 obvious that any desired number may be provided and that they will serve to retain the stencils in position while yet offering but a negligible resistance to their passage.

20 Thus it will be seen that the novel form of track herein described and shown will enable any addressing machine of the second (side-to-side) type to be adapted to the use of tabbed stencils.

25 It will be understood that various changes may be resorted to in the form, construction and arrangement of the several parts without departing from the spirit and scope of my invention; hence, I do not intend to be limited 30 to the details herein shown and described except as they may be included in the claims.

What I claim is:

1. In an addressing machine, a stencil provided with a projecting tab and a track for 35 guiding the stencil, said track including a recessed portion adapted to receive an edge of the stencil and a recessed portion adapted to receive the projecting tab, the portion first named being bounded laterally by an undercut wall.

2. In an addressing machine, a stencil track including, a recessed portion adapted to receive an edge of a stencil, a recessed portion adapted to receive a projection from 45 the edge of the stencil, and means for holding the stencil down steady in the recessed portion first named.

3. In an addressing machine, a stencil provided with a tab projecting therefrom in a 50 plane substantially parallel to the central plane of the stencil, and a track for guiding the stencil and tab, said track including a recessed portion adapted to receive an edge of the stencil and another recessed portion 55 adapted to receive the projecting tab.

4. In an addressing machine, a stencil provided with a projecting tab, and a track for 60 guiding the stencil, said track including a recessed portion adapted to receive an edge of the stencil, a recessed portion adapted to receive the projecting tab, and means for holding the stencil down steady in the recessed portion first named.

5. In an addressing machine, a stencil provided with a projecting tab, and a track for 65

guiding the stencil, said track including a recessed portion adapted to receive an edge of the stencil, a recessed portion adapted to receive the projecting tab, and a yielding pressure device for holding the stencil down steady in the recessed portion first named. 70

6. In an addressing machine, a stencil provided with a projecting tab, and a track for 75 guiding the stencil, said track including a recessed portion adapted to receive an edge of the stencil, a recessed portion adapted to receive the projecting tab, a top plate extending above the edge of the stencil, and a yielding pressure device carried by said plate for holding the stencil down steady in the 80 recessed portion first named.

7. In an addressing machine, a stencil track including a lower horizontal portion adapted to support an edge of a stencil, an undercut wall portion designed to retain the stencil against displacement, an upper horizontal portion and upper vertical portion providing a recess for the accommodation of a projection from the edge of the stencil, and a top plate extending above the edge of the 85 stencil. 90

8. In an addressing machine, a stencil provided with a projecting tab, and a track for 95 guiding the stencil, said track including a lower horizontal portion adapted to support an edge of the stencil, an undercut wall portion designed to retain the stencil against displacement, an upper horizontal portion and upper vertical wall portion providing a recess for the accommodation of the projecting tab, and a top plate extending above the edge of the stencil. 100

9. In an addressing machine, a stencil provided with a projecting tab, and a track for 105 guiding the stencil, said track including a lower horizontal portion adapted to support an edge of the stencil, an undercut wall portion designed to retain the stencil against displacement, an upper horizontal portion and upper vertical wall portion providing a recess for the accommodation of the projecting tab, a top plate extending above the edge of the stencil, and a yielding pressure device carried by said plate for holding the edge of the 110 stencil down steady upon the lower horizontal portion. 115

In testimony, that I claim the foregoing as my invention, I have signed my name this 13th day of October, 1927.

ALBERT E. STRIPPEL. 120
